2 SHEETS—SHEET 2.

This technical drawing illustrates a mechanical assembly, likely a component of a larger machine. The drawing is labeled with various numbers and letters, indicating different parts and their connections.

- Top Left:** A vertical line labeled "cable" is connected to a horizontal line labeled "22".
- Top Center:** A vertical line labeled "23" is connected to a horizontal line labeled "24".
- Top Right:** A vertical line labeled "25" is connected to a horizontal line labeled "26".
- Center:** A vertical line labeled "27" is connected to a horizontal line labeled "28".
- Right Side:** A vertical line labeled "29" is connected to a horizontal line labeled "30".
- Bottom Left:** A vertical line labeled "31" is connected to a horizontal line labeled "32".
- Bottom Center:** A vertical line labeled "33" is connected to a horizontal line labeled "34".
- Bottom Right:** A vertical line labeled "35" is connected to a horizontal line labeled "36".
- Bottom Left Labels:** The labels "T", "4", "9", and "4" are positioned near the bottom left corner.
- Bottom Center Labels:** The labels "7", "5", "9", and "8" are positioned near the bottom center.
- Bottom Right Labels:** The labels "10", "E", and "E'" are positioned near the bottom right corner.

UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

ELECTRIC TELEGRAPHY.

No. 902,871.

Specification of Letters Patent.

Patented Nov. 17, 1908.

Application filed July 8, 1905. Serial No. 268,300.

To all whom it may concern:

Be it known that I, ISIDOR KITSEE, a citizen of the United States, residing in the city and county of Philadelphia and State of Pennsylvania, have invented a new and useful Improvement in Electric Telegraphy, of which the following is a specification.

My invention relates to the art of telegraphy and especially to the practice of telegraphy over long lines or cables in which the disturbing effects of capacity are comparatively great.

It is the object of my invention to increase the speed of a line or cable, and to this end the transmitted electrical impulses are preferably short and all of practically the same duration, the intervals of time or spaces between impulses being resorted to for distinguishing the elements of the various code characters.

It is well known that on long lines or cables, and especially submarine cables, telegraphy by the utilization of electric impulses all of the same polarity is impossible if any substantial speed is to be attained, because of the difficulty of distinguishing between long and short impulses. It is the practice at present to represent one element of the Morse code, say the dot, by a negative impulse, and another element, say the dash, by a positive impulse. In such system it very frequently occurs, however, that two or more successive impulses of the same polarity must be transmitted.

In my system, the two elements of the Morse code, the dot and the dash, may be recorded without resorting to impulses of different durations.

In practicing my invention on lines where the disturbing effect of capacity is not very great, impulses of one polarity only may be employed. When applying my system to submarine cable telegraphy, however, where the effects of capacity are relatively very great, it is preferable to employ both polarities.

My invention will be better understood by reference to the accompanying drawings in which:—

Figure 1 is a table of spaces representing the elements of code characters. Fig. 2 represents a tape transmitter by which impulses of one polarity only are transmitted. Fig. 3

represents a tape transmitter in which the impulses of both polarities are transmitted. Fig. 4 represents a portion of the receiving tape having thereon a record corresponding with the word "greeting" in the continental Morse code. Fig. 5 is a diagrammatic view of the receiving apparatus when the signals or messages are to be read by sound. Fig. 6 is a diagrammatic view of the transmitting and receiving apparatus employed in connection with a submarine or other cable.

Referring to Fig. 1, *a* represents a dot, as represented in the receiving recording apparatus, when such dot occurs at the beginning or within a code character. *b* represents a dash as recorded in the receiving apparatus, when the dash occurs at the beginning of a code character or occurs within it. *c* represents the record of a dot when such dot occurs alone or at the end of a code character. In other words, *c* represents a dot and the space between it, when the last element of a code character, and the first element of a succeeding code character. Similarly, *d* represents a dash when it occurs alone or is the last element of a succeeding code character. In other words, *d* represents a dash and the space occurring between such dash and the first element of the succeeding code character. If reading by sound, *a*, *b*, *c*, and *d* represent durations of strokes of the sounder under the aforementioned conditions. 85

Referring to Fig. 2, *T* is a tape perforated as hereinafter described and adapted to travel over the cylinder 1 of conducting material which is continuously in electrical communication with the line or cable through the conductor 2. The brush 3 bears upon the tape and is adapted to make contact with the cylinder 1 whenever a perforation in the tape *T* passes under the brush 3. The brush 3 is connected to one terminal of the battery or other source of electrical energy *B* whose other terminal is connected to earth at *E*, or a second line or cable if a metallic return is employed. 90

Since the received signals or messages are distinguished by the intervals of time between transmitted impulses, such transmitted impulses may be relatively short, and all of practically uniform duration. In consequence, the tape *T* is perforated with successive holes represented as circular and des-

ignated by the reference character 4. As each perforation passes beneath the brush 3, an impulse will be sent to line. Since it is the space between impulses that represents an element of a code character, or an element and a space, the perforations in the tape T will succeed each other by distances chosen in accordance with the table in Fig. 1.

To represent the word "greeting" the spacing of the perforations is shown in Fig. 2, the spaces between successive perforations being designated in accordance with Fig. 1.

In Fig. 3, T is a tape adapted to pass over the conducting cylinder 5 which is in continuous electrical communication with the line or cable through the conductor 6. A brush 7 bears upon tape T and is connected to one terminal of the battery 8 whose other terminal connects to the earth or return conductor E. Similarly 9 is a brush bearing upon the tape T and connected to one terminal of the battery 10 whose other terminal connects to earth or the return conductor E.

The perforations in the tape T are arranged in two columns, one column passing under the brush 7 and the other under the brush 9 so that alternate positive and negative impulses are transmitted to line, the spacing between succeeding impulses being, however, the same as in the case of Fig. 1. Thus the perforations shown in Fig. 3 also represent the word "greeting" except that the transmitted impulses are alternately positive and negative so that the line or cable is more quickly responsive, that is, it is capable of operating at a higher speed than if successive impulses of like polarity were transmitted.

Fig. 4 represents the record tape at the receiver when either of the transmitters shown in Figs. 2 and 3 are employed. Normally on the receiving tape a continuous practically straight line is drawn. Upon the arrival of each impulse, the continuous line is interrupted as shown in Fig. 4, thus in effect producing record elements corresponding with the elements shown in Fig. 1, these elements being then easily translated into a signal or message.

Referring to Fig. 5, 11 represents the end of the line or cable at the receiving station, and in series between the same and the earth or return conductor E is connected the winding of the relay R whose armature 12 is held retracted by the spring 13 against the back stop 14 thus normally holding a circuit including the battery 15, and the winding of a sounder magnet 16 closed. When an impulse is transmitted over the line, the armature 12 is momentarily attracted toward or against the front stop 17 of the relay R thus momentarily interrupting the circuit of the magnet 16. In consequence the sounder armature 18, which is normally attracted in opposition to the spring 19, is released and

strikes the back stop 20 and is then immediately again attracted against the front stop 21. As the successive impulses arrive, this operation is repeated, and the message is read by sound by distinguishing the intervals of time during which the armature 18 is allowed to remain against the stop 21.

Referring to Fig. 6, T represents a tape, 5 a conductive cylinder, 7 and 9 brushes, 8 and 10 batteries, and E the earth or return conductor as in Fig. 3. Successive impulses of alternate polarities are transmitted by this apparatus over the line or submarine cable 22 which is connected at the receiving end through the siphon recorder coil 23 to earth or return conductor E'. As well understood in the art of cable telegraphy, the coil 23 is suspended in the strong magnetic field existing between the pole pieces 23, 25, and the internal core 26. When the arriving impulses pass through the coil 23, such coil will rotate slightly, the direction of rotation being dependent upon the polarity of the received impulses. 27 is a connector between the coil and the siphon 28 which dips at its one end into ink in the well 29. The outer end of the siphon is adapted to oscillate under the control of the coil 23 transversely of the tape T' which travels in the direction indicated by the arrow. At 30 is represented a shield having the hole 31 and the drain or groove 32 as described in Letters Patent of the United States No. 792052 heretofore granted to me.

The operation is as follows:—Normally the outer end of the siphon 28 is opposite or registers with the hole 31 in the shield 30 and as the tape T moves along, a continuous and practically straight line record is produced. At the arrival of each impulse however, the coil 23 oscillates either to the right or to the left and therefore moves the siphon 28 away from the hole 31 in the shield 30, thus causing interruptions in the continuity of the line record. It is immaterial which way the coil 23 moves, or in other words, the line record is independent of the polarity of the transmitted impulses. As heretofore stated, the transmitted impulses are alternately positive and negative in order to make the cable or line operate at a higher speed. The tape record T is similar to that shown in Fig. 4, and is translated by having recourse to the table in Fig. 1. From the foregoing description it is apparent that in my system it is the spaces or intervals between line impulses that are employed to represent a message, the line impulses succeeding each other at suitable intervals in accordance with the different code character elements. It is also apparent that the received message is independent of the polarity of the transmitted impulses.

By this system, the speed of signaling, es-

pecially over submarine cables is materially increased. Skill in translating the new form of record is easily and quickly acquired.

What I claim is:—

- 5 1. In a cable telegraph system, means for impressing alternate positive and negative impulses of practically uniform duration upon a cable, the intervals between successive impulses serving to designate elements 10 of the code characters, and a polarized siphon recorder normally tracing a continuous line and responsive alike to received positive and negative impulses to interrupt said line to represent elements of code characters.
- 15 2. In a cable telegraph system, means for impressing alternate positive and negative impulses of relatively short and practically uniform duration upon a cable, and a polarized siphon recorder normally tracing a continuous line and responsive alike to received positive and negative impulses to interrupt said line to represent elements of code characters.
- 20 3. In a cable telegraph system, means for impressing alternate positive and negative impulses of relatively short and practically uniform duration upon a cable, and a polarized recorder normally tracing a continuous line and responsive indifferently to all impulses to render said line discontinuous to represent signal elements.
- 25 4. In a cable telegraph system, means for impressing successive electrical impulses alternating in polarity and of practically uniform duration upon a cable, the intervals between successive impulses serving to designate elements of a signal, and a polarized recorder normally tracing a continuous and 30 practically straight line and responsive in-

differently to all impulses to alter said line, spaces between line alterations representing signal elements.

5. In a cable telegraph system, means for impressing alternate positive and negative impulses of practically uniform duration upon a cable, and a polarized recorder normally tracing a continuous line and responsive to all impulses to interrupt said line, the resultant gaps in said line being of approximately equal length.

6. In a cable telegraph system, the combination with the cable, of means for impressing thereon successive impulses of opposite polarities and of practically uniform duration, and receiving apparatus comprising a polarized receiving instrument normally tracing a continuous line and responsive to all impulses to interrupt said line, whereby gaps result in said line, said gaps being of approximately equal length.

7. In a cable telegraph system, the combination with the cable, of means for impressing thereon electrical impulses alternating in polarity and of practically uniform duration, the intervals between successive impulses serving to designate elements of a signal, and receiving apparatus comprising a polarized receiving instrument normally tracing a continuous line and responsive to all impulses to produce gaps in said line, the gaps in said line being approximately equal.

In testimony whereof I have hereunto affixed my signature in the presence of the two subscribing witnesses.
